UNITED STATES PATENT OFFICE.

WILLIAM DIEMER, OF TOLEDO, OHIO, ASSIGNOR TO THE GENDRON WHEEL COMPANY, OF SAME PLACE.

CHILD'S CARRIAGE.

SPECIFICATION forming part of Letters Patent No. 633,817, dated September 26, 1899.

Application filed October 31, 1898. Serial No. 695,073. (No model.)

To all whom it may concern:

Be it known that I, WILLIAM DIEMER, a citizen of the United States, residing at Toledo, in the county of Lucas and State of Ohio, have 5 invented certain new and useful Improvements in Children's Carriages, of which the following is a specification, reference being had therein to the accompanying drawings.

The invention relates to that class of children's carriages known to the trade as "go-carts," in which the body thereof constitutes a chair provided with a footboard on which the feet of the occupant normally rest and having attached thereto at the rear the usual push-handles.

The object of my invention is to so form a vehicle of the type referred to that the position of the child therein may be changed from an upright one to a recumbent position without the necessity of moving or lifting the child.

With this object in view my invention consists in an improved child's carriage and in the peculiar arrangement and combination of the various parts thereof.

Figure 1 is a vertical longitudinal section of my improved child's carriage, showing it as arranged for the recumbent position of the child. Fig. 2 is an enlarged vertical longitudinal section of the chair-seat with the sliding foot-supporting shelf concealed beneath the seat. Fig. 3 is a cross-section on line xx , Fig. 2. Fig. 4 is a horizontal section and plan on line yy , Fig. 1. Fig. 5 is a detached perspective 35 view of a folding brace.

The chair-body consists of the seat-frame A, the sides B, the back C, and the rearwardly-projecting push-handles D, all arranged in known manner except as more fully herein-40 after described. This chair-body is rigidly supported in front upon an axle E by means of bracket-arms G, and in rear it is supported upon the axle H by means of the helical springs J, and front and rear wheels are 45 journaled upon these axles to support them on the ground. In front below the seat-body a footboard K is vertically adjustably secured upon the bracket-supports G, and a strap L is provided which may be fastened 50 across the front of the seat, all so arranged that a child may be secured in the chair-body

in a sitting position with the feet resting upon the board.

My invention consists in providing the chair-body with means for readily converting 55 it into an easy and comfortable couch without the necessity of lifting or moving the child, and this I accomplish in the following manner:

Below the seat-frame A of the body I provide a supporting frame or shelf M, slidably held in longitudinal guides N, which are secured on the under side of the seat-frame. This frame at its front is provided with an end board O, extending the width of the seat-frame and adapted to form a skirting in front thereof when the frame M is normally concealed below the seat-frame, as shown in Fig. 2, at the same time forming a convenient handhold for manipulating the frame M.

In the longitudinal center on the under side of the seat-frame is secured a spring-wire P, which has crimps Q formed in it, operating in connection with suitable cross-bars R R to lock the sliding frame in either of its extreme 75 positions.

In connection with the foot-supporting shelf I provide the body with a reclining back. To this end I form the back C with a separate or independent frame entirely disconnected 80 from the sides of the body, and this frame I hinge at the lower end to the rear end of the seat-frame and connect it at the sides by triangular web S between the posts T of the side frames and the posts T' of the back, all so 85 arranged as to permit the back to be moved on its hinges from the position shown in dotted lines to the position shown in full lines in Fig. 1.

To hold the back C in either of its adjusted 90 positions, folding braces U may be used, Fig. 5, showing a well-known construction, in which the ends a b are pivotally secured to the post T and post T', respectively, and which interlock when folded by means of a spring-95 catch c. In practice the chair-body is readily converted by these means from its ordinary adjustment as a seat into the form of a convenient couch, and the desirability of a go-cart is thereby greatly increased.

What I claim as my invention is—
1. In a child's carriage, the combination of

a wheeled supporting-frame provided with rearwardly-projecting push-handles, a child's chair mounted thereon and fixedly secured thereto, comprising a seat-frame and a back 5 and sides therefor, and a rigid extensible foot-supporting shelf slidably engaging the frame beneath the seat for endwise movement in a plane parallel to the plane of said seat, and supported by the frame in its extended positions.

2. In a child's carriage, the combination of a wheeled supporting-frame provided with rearwardly-projecting push-handles, a child's chair mounted thereon and fixedly secured thereto, comprising a seat-frame and a back 15 and sides therefor, a rigid extensible foot-supporting shelf slidably engaging the frame beneath the seat for endwise movement in a plane parallel to the plane of said seat, and supported by the frame in its extended positions, and means for locking said shelf to the frame after the required extension has been made.

3. In a child's carriage, the combination of a wheeled chair-body comprising a seat-frame, 25 sides, a back, and push-handles secured to the seat-frame and extending rearwardly of the back, a seat-frame extension slidably secured in longitudinal guides beneath the seat-frame and the end board O on the front end of said extension seat-frame.

4. In a child's carriage, the combination of the chair-body comprising the seat-frame A, the sides B, the back C, the extension seat-frame 35 slidably secured in longitudinal guides beneath the seat-frame and provided with the end board, O, and the locking-spring P for holding said extension-frame in its adjusted positions.

In testimony whereof I affix my signature 40 in presence of two witnesses.

WILLIAM DIEMER.
